UNITED STATES PATENT OFFICE.

EVERETT WORTHINGTON, OF SAN FRANCISCO, CALIFORNIA.

STORE COUNTER.

1,411,765.

Specification of Letters Patent.

Patented Apr. 4, 1922.

Application filed February 16, 1921. Serial No. 445,395.

To all whom it may concern:

Be it known that I, EVERETT WORTHINGTON, a citizen of the United States, and a resident of the city and county of San Francisco and State of California, have invented 5 a certain new and useful Store Counter, of which the following is a specification.

This invention relates to store furniture and particularly to counters for display and 10 stockholding and storage purposes.

It is one of the objects of the present invention to provide an improved store counter, that may be readily erected of a series of substantially duplicate units or sections so 15 that a counter may be erected of any given length and readily altered with great convenience and at small expense.

A further object of the invention is to provide a sectional counter formed of units, 20 each being constructed of knock-down members.

A further object of the invention is to provide a counter unit or section the several 25 members or elements of which are constructed according to standardized system so as to be readily interchangeable with other units and to match with units of complementary and adjacent sections. A further object is to provide unit members or elements 30 that can be compactly stored and shipped for economy in transportation and storage space and which, at the same time, can be readily erected to form a substantial, ornate and capacious counter unit or section. In 35 this connection it is a further object to provide complementary and cooperative structural members adapted when assembled to interlock in a substantial manner so that the whole will be stable and secured without the 40 requirement of extraneous removable fastening devices.

It is a further object to provide a counter of such depth from front to back as to provide a capacious storage chamber and also to 45 provide means in the chamber adjustable transversely with respect to the front and back of the counter to form a backing or follower to facilitate storage and removal of goods from the counter chamber.

The invention possesses other objects and 50 features of advantage, some of which, with the foregoing, will be made manifest in the following description of the preferred form of the invention which is illustrated in the 55 drawings accompanying and forming part of the specification. It is to be understood

that it is not intended to limit the invention to the embodiment shown by the said drawings and description as variations may be adopted within the scope of the invention 60 as set forth in the claims.

Referring to the drawings:

Fig. 1 is a perspective of a complete erected unit.

Fig. 2 is a front elevation of a counter 65 formed of a plurality of the units, one of which is broken away.

Fig. 3 is a perspective looking toward the rear of a unit and showing the top member tilted upwardly and also showing the back 70 frame removed from its proper position.

Fig. 4 is a perspective showing the top member tilted upwardly on one end and illustrating a dismounted side member and 75 dismounted back frame and back panel.

Fig. 5 is a horizontal section through the rear portion of one of the side members and showing a pair of the back frames applied thereto.

Fig. 6 is a horizontal sectional view of a 80 portion of the front end of a side with a pilaster and indicating the attachment of the front members thereto.

The present invention consists generally of a counter construction formed of a plurality 85 of sections or units that may be conveniently and quickly arranged end to end substantially without interconnection or interlocking and presenting an ornamental and continuous front so that a number of sections 90 or units can be alined to form a counter of suitable length. Again, the invention consists of the provision of a section or unit formed of a plurality of coordinate structural members adapted to be quickly assembled, certain of which are interlocked to 95 provide a substantial, firm and capacious display and storage counter section or unit. The invention also involves other details, but one form of the invention being illustrated herein though it is obvious that the unit members may be constructed in any desired dimensions and proportions and of suitable design according to given requirements.

In Figure 4 the various elements or members constituting a unit are shown in dismounted and partly assembled position. Each unit consists of a substantially rectangular bottom-forming base or pedestal 110 2 having vertical side pieces upon which is mounted the bottom 3. Along the front of

the base 2 is a foot or facing strip 4 which projects upwardly slightly above the plane of the bottom 3. Adjustable against the upwardly extending portion of the facing strip 4 is an upright front panel 5 of somewhat less length than the length of the facing strip 4.

To aid in maintaining the front panel 5 in upright position the stiles or end portions of the front panel are adapted to interengage with and interlock suitable means here shown as in the form of side panels or members 6—6 adapted to be mounted in vertical and transverse position across the ends of the bottom 3 of the base. The front vertical portions of the side members 6—6 are each preferably provided with ornamental post devices or pilasters of somewhat greater width than the thickness of the respective side panel or member 6 as clearly shown in Fig. 6, at 7, and interposed between the pilaster and the side panel 6 is a post 7' of lesser width than the pilaster at its forward side, and provided at its rearward side with ribs or shoulders 8—8, the front faces of which are beveled off away from the pilaster to form a narrowing groove into which the edges of the front panels 5 extend. At their side edges, the front panels 5 are thickened on their rear faces to form wedge-like edges, so that as the edges are entered into the grooves, the front panels are pressed forward tightly against the rear face of the pilaster.

35 To further interlock the side members 6—6 with the adjacent pilasters 7 these latter may be provided with key slot plates 9 forming keepers to take hooks 10 extending from the ends of the front panel 5.

40 When the base 2 with the front panel 5 and the side members 6—6 have been assembled, as shown in Fig. 3, there may be then applied to the top edges of these members a top structure 11 of any suitable shape and 45 which is here shown as of hollow structure forming a chamber 12 open at the rear for access to contents thereof. The top structure may have a bed 13 from the lower portion of which extends downwardly a plurality of lugs or dowels 14 disposed to match with dowel holes 15 provided therefor in the top edges of contiguous elements such as the side members 6—6. At the front portion of the bed 13 there may be provided a 55 longitudinally extending tenon 16 to bear upon or approach the top end surface of the pilasters 7; which surfaces are slightly below the plane of the top edges of the side members 6.

60 Before the top structure 11 is lowered into interlocking position upon the side members 6 there is applicable to the open rear portion of the counter, thus constructed, a suitable door frame 17 which, when inserted in 65 its final position, will bear against the con-

tiguous ends of transversely extending cleats or rails 18 and 19; the upper and lower transverse members of the frame 17 being provided with dowel pins 20 to enter dowel holes 21 in the adjacent structure. As 70 shown in Fig. 5, each frame 17 may be rebated at 17^a to take the contiguous end edges of adjacent elements as the side members 6; the rear and outer corners of the frame being beveled away as at 17^b so as to form a neat 75 finish at the back of the counter. When the frames 17 are of considerable dimensions their openings may be subdivided as by suitable doors 23, which are preferably hinged to the frame. 80

The vertical stiles of the frame 17 are shown as provided with series of transversely extending notches 24 which, when the frame is applied to the unit, will be in opposition to notches 25 in side members 6; 85 the sets of notches being designed to receive a vertically adjustable shelf 26, or a series of shelves of which only one is shown.

A shelf, as 26, may be disposed in the notches as above described or it may be disposed upon opposite transverse cleats 19, as 90 shown in Fig. 3. When a counter unit as above described is of considerable depth between the front and the back it is desirable to prevent the stock of material that may be 95 placed therein from becoming disarranged. Also, it is desirable to provide for the stacking or piling of certain classes of material either with or without containers so that they may be readily accessible without having to reach far forwardly under the top structure 11 and to that end an adjustable follower or transversely extending partition is provided. Such a partition is shown 100 as comprising an upright panel or board 30 105 the bottom edge of which may bear upon the shelf 26 over which it may be moved toward or from the back as desired. Suitable means may be employed to maintain the follower 30 in upright position at various 110 locations between the front and back of the counter. Such means is here shown as comprising a set of runners or slides, each having a channel shaped portion 31, Fig. 3, 115 engaging a portion of the horizontal top rail 18, which is shown as slotted at 18', to receive one flange of the channel while the other flange passes beneath the bottom of the rail 18. Disposed at right angles to the channel portion 31 each runner has a pair 120 of parallel upright flanges 32 to embrace the end of the partition 30.

The ends of the shelf 26 are similarly mounted on runners 33 having flanges 34 the latter running on the cleats 19 and 125 each of the runners 33 being provided with a pair of vertically disposed flanges to embrace the ends of the partition 30.

From the above it will be seen that the invention provides for the compact storage 130

and packing of the several elements comprising a unit, thus saving in transportation space and storage space and yet providing for the ready assembling and secure interlocking of the various elements to form a complete unit a series of which may be arranged end to end to form a counter of desirable length.

What is claimed is:

- 10 1. A unit section, for a store counter, having a rigid base including a bottom having a rebated top edge, side members adapted to be erected on the rebated ends of the base, a front member to interlock with the side members, a top member adapted to be set down on and to interlock with the side members and front, and a back closure to interlock with the assembled top and bottom members.
- 20 2. A unit section, for a store counter, having a rigid base, side members adapted to be erected on the ends of the base, a front

member to interlock with the side members, a top member adapted to interlock with the side members, a back frame to interlock 25 with the assembled top and base members, and back panels removably mounted on the frame.

3. A store counter having horizontal cleats on side walls, an upright follower adjustable to selective position transversely across the cleats and runners slideable on the cleats and holding said follower upright.

4. A store counter having a horizontal part, an upright follower adjustable to selective position transversely across the part, runners having guided, sliding relation with said part and holding the follower upright, and runners at the upper portion of the follower for sustaining it.

In testimony whereof, I have hereunto set my hand.

EVERETT WORTHINGTON.
